LAPPING MACHINE

Herbert S. Indge, Westboro, Mass., assignor to
Norton Company, Worcester, Mass., a corpora-
tion of Massachusetts

Application July 9, 1940, Serial No. 344,554

6 Claims. (Cl. 51—55)

The invention relates to lapping machines, and more particularly to a lapping machine for producing highly refined plane surfaces on a work piece.

One object of the invention is to provide a simple and thoroughly practical lapping machine in which a plane surface of a relatively large work piece may be rapidly surfaced to a plane surface of extremely high quality. Another object of the invention is to provide a lapping machine in which the work piece is rotated and gyrated in a rotary or irregular path while being lapped or abraded by a plurality of rotary and planetarily moved lapping elements or by a reciprocating lapping element which is reciprocated with a compound reciprocating movement. Another object of the invention is to provide a lapping machine for finishing plane surfaces by means of a lapping element which is reciprocated by means of a compound reciprocating movement, that is, a relatively fast reciprocating movement to which is superimposed a slower reciprocating movement of a slightly shorter stroke.

Another object of the invention is to provide a lapping machine for finishing relatively large work pieces by applying a plurality of lapping elements thereto which are reciprocated with a compound reciprocating movement and simultaneously oscillated in arcuate paths relative to the surface of the work piece being lapped. Other objects will be in part obvious and in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is a right-hand end elevation of the improved lapping machine equipped with rotatable lapping wheels, having parts broken away and shown in section to show the operating mechanism thereof;

Fig. 2 is a front elevation of the improved lapping machine equipped with reciprocating lapping stick adapters;

Fig. 3 is a fragmentary diagrammatic view, showing the hydraulic piping diagram and electrical control circuit of the machine;

Fig. 4 is a fragmentary plan view, showing the driving mechanism for the lapping heads

Fig. 5 is a fragmentary vertical sectional view, on an enlarged scale, of the driving and operating mechanism for one of the lapping heads;

Fig. 6 is a fragmentary cross-sectional view, 60

taken approximately on the line 6—6 of Fig. 5, showing the driving mechanism for producing a slow rotation of the lapping wheel;

Fig. 7 is a fragmentary bottom view, on an enlarged scale, having parts broken away and shown in section, of the reduction gear unit for controlling the simultaneous oscillation of the lapping heads;

Fig. 8 is a cross-sectional view, taken approximately on the line 8—8 of Fig. 7;

Fig. 9 is a fragmentary sectional view, on an enlarged scale, of the gear mechanism for simultaneously oscillating the lapping heads;

Fig. 10 is a fragmentary view showing the arrangement of the control lever for actuating the cycle start switch and the stop switch;

Fig. 11 is a fragmentary vertical sectional view, on an enlarged scale, through one of the lapping heads equipped with a reciprocating stick adapter;

Fig. 12 is a fragmentary front elevation, on an enlarged scale, showing the reciprocating lapping stick adapter;

Fig. 13 is a cross-sectional view, on an enlarged scale, taken approximately on the line 13—13 of Fig. 11;

Fig. 14 is a fragmentary sectional view, on an enlarged scale, taken approximately on the line 14—14 of Fig. 11; and

Fig. 15 is a fragmentary front elevation, showing the two lapping heads equipped with lapping wheels.

The improved lapping machine illustrated in the drawings comprises a base 10 which supports a rotatable work supporting platen 11 together with a plurality of work driving pins or studs 12 (only one of which is shown in the drawings) which engage apertures in a work piece 13 to be finished. The platen 11 is positively driven by means of an electric motor 14 mounted within the base 10 of the machine. The motor 14 is preferably mounted on a pivotally-mounted adjustable motor support 15 (Fig. 1) which is supported on a stud or shaft 16. The motor 14 is provided with a driving pulley 19 which in turn serves to rotate a worm 20 (Fig. 3). The worm 20 meshes with a worm gear 21 and serves to drive the work supporting platen 11 and revolve and gyrate the work driving pins 12 by means of a mechanism substantially the same as that shown in my prior U. S. Patent No. 1,610,527 dated December 14, 1926. The details of the mechanism for rotating the work supporting platen 11, which in my prior patent is a lapping element 11, and for rotating and revolving the work driving pins 12, have not been illustrated in the present case since it is not considered to be a part of the present invention. For details of disclosure not

contained herein, reference may be had to my prior patent above referred to.

A pair of spaced lapping heads 25 and 27 (Fig. 2) are provided for supporting either a lapping wheel or a reciprocating lapping stick adapter (to be hereinafter described) so as to present a plane operative end face to lap or abrade the work piece 13. In the preferred construction, a pair of spaced micro-lapping heads are provided including in addition to a head 25 a micro-lapping head 27 which serves as a support for a lapping wheel 28 or a reciprocating lapping stick adapter which is also arranged to present a plane operative face. The lapping wheels 28 (only one of which has been illustrated in Figs. 1 and 3) are spaced from each other and are arranged to engage the work piece 13 to be lapped at diametrically opposite positions. Each of the lapping wheels 28 is mounted for a combined rotary and planetary movement so that the abrading or lapping surface is moved in an irregular path as the work piece is rotated and gyrated. Each of the heads 25 and 27 is identical in construction, consequently only one of the heads has been illustrated in detail. The lapping wheel 28 (Fig. 1) is supported at one end of a rotatable spindle 29 which is journaled in an eccentrically mounted bearing 30 within a rotatable sleeve 31. The sleeve 31 is rotatably supported in bearings 32 and 33 within the frame of the head 27. The wheel 28 is similarly mounted at the lower end of a rotatable spindle which is similarly journaled in eccentrically positioned bearings within a rotatable sleeve which is in turn rotatably supported within the frame of the head 25.

Both of the heads 27 and 25 are arranged so that the rotatable sleeves 31 may be rotated at a relatively fast speed while the eccentrically mounted spindles 29 contained therein are rotated at a relatively slow speed so that the individual abrasive grains of the lapping wheels 26 and 28 will be moved in irregular paths while in operative contact during the rotary and gyratory movement of the work piece 13.

The lapping heads 25 and 27 are preferably arranged so that they may be moved in a substantially vertical direction toward and from the work piece 13. A hollow column 36 is rigidly fixed to the upper surface of the base 10. A vertically movable hollow sleeve 37 is slidably mounted within the column 36 and is arranged to support the lapping heads 25 and 27 adjacent to its upper end. The sleeve 37 supports a bracket 38 which serves as a support not only for the lapping heads 25 and 27 but also supports the driving mechanism therefor to be hereinafter described.

In addition to the rotary and planetary movement of each of the lapping wheels 26 and 28, it is desirable that the heads 25 and 27 be simultaneously oscillated to impart a third movement to the lapping wheels 26 and 28, thus aiding in providing a further irregular break-up motion of the lapping elements to produce a highly finished workpiece. The heads 25 and 27 are each provided with rearwardly extending arms 39 and 40, respectively, which are pivotally supported on a sleeve 41a (only one of which is shown in detail in Fig. 1). The bushing or sleeve 41 is vertically arranged and is rotatably supported by the bracket 38. The arms 39 and 40 are preferably arranged as bell crank levers having inwardly projecting arms 41 and 42, respectively (Fig. 4). The inner ends

of the arms 41 and 42 are each provided with intermeshing gear segments 43 and 44 by means of which the arms 39 and 40 together with the heads 25 and 27, respectively, and the lapping wheels 26 and 28 may be simultaneously oscillated in opposite directions during the lapping operation to impart a relative oscillating movement to each of the heads 25 and 27 during the rotary and planetary movement of the lapping wheels supported thereby.

The frame 38 has a rearwardly extending portion 48 (Fig. 4) which serves as a support for an electric driving motor 49. The motor 49 is provided with a driving pulley 50 which is preferably a multisteped V-type pulley (Fig. 1) which is connected by a V-belt 51 with multiple stepped V-pulleys 52 and 53, respectively. The pulleys 52 and 53 are supported by vertically arranged shafts or spindles 54 and 55, respectively, which are rotatably journaled in the sleeves 41.

The spindle or shaft 55 also supports a single V-groove pulley 56 (Fig. 4) which is connected by a V-belt 57 with a single V-groove pulley 58 which is mounted on and adjacent to the upper end of the sleeve 31 to rotate the sleeve 31 and thereby carry the spindle 29 and the lapping wheel 28 supported thereby in a planetary path. Similarly, the spindle or shaft 54 (Fig. 4) is provided with a single V-groove pulley 59 which is connected by means of a V-belt 60 with a single V-groove pulley (not shown) which is mounted on the rotatable sleeve supporting the lapping wheel spindle 35 to rotate the sleeve and thereby move the spindle 35 and the lapping wheel supported thereby in a planetary path. This planetary drive for the head 25 has not been illustrated in detail, since it is identical to that shown in Fig. 1 for the head 27.

To facilitate a relatively slow rotary movement of the lapping wheels 26 and 28 during their planetary movement, the sleeve 31 is provided with a reduced cylindrical portion 65 which is concentric with the axis of the wheel spindle 29. This portion 65 serves as a support for an anti-friction bearing 66 which in turn supports a rotatable sleeve 67. The sleeve 67 carries a gear 68 which is fixedly mounted thereto and which meshes with a stationary internal ring gear 69 carried by the frame of the head 27. The size of the gear 68 is such that it continuously meshes with the gear 69 during the planetary movement of the spindle 29 as produced by rotation of its supporting sleeve 31. The gear 68 has a smaller number of teeth than the fixed gear 69 so that as the gear 68 revolves within the stationary gear 69, the very slow rotary movement is imparted to the lapping wheel spindle 29 to produce a relatively slow rotary movement of the wheel 28 while it is being moved planetarily at a comparatively rapid rate.

The sleeve 67 is slidably keyed to the spindle 29 by means of a key 70 so that the spindle may be moved in a vertical direction to apply the desired pressure to the lapping wheel 28 while in operative engagement with the work piece 13. The upper end of the wheel spindle supports an anti-friction bearing 72 which in turn rotatably supports the casing 73 having a cover plate 74 fixedly mounted thereon. A compression spring 75 is supported at its lower end by means of a stud 76 fixedly mounted on or integrally formed with the cap or cover 74. The upper end of the spring 75 is supported by a reduced cylindrical portion or stud 77 formed at

the lower end of the sleeve 78. The sleeve 78 is screw threaded within the upwardly extending housing 79. A nut 80 threaded onto the sleeve 78 serves to lock the sleeve 78 in adjusted position relative to the housing 79, so that after the spring 75 has been compressed as desired it may be locked in adjusted position.

It is desirable to provide a suitable mechanism for raising the wheel spindle 29 vertically to compress the spring 75 and withdraw the wheel 28 from operative contact with the work when desired. As illustrated in Fig. 5, a link chain 82 is fastened at its lower end to the stud 76. The upper end of the chain 82 is connected to a pivotally mounted block 83 which is pivotally supported by means of a stud 84. The stud 84 is supported on an upwardly extending boss 85 formed integral with the sleeve 78. The bracket 83 is provided with an actuating handle 86 whereby when moved in a clockwise direction (Fig. 5), the chain 82 may be pulled upwardly in a vertical direction to compress the spring 75 and thereby raise the spindle 29 and the lapping wheel 28 from operative engagement with the work piece. An identical construction is provided for rotating the wheel spindle 35 and also for raising it in a vertical direction. It is, therefore, deemed unnecessary to duplicate illustration of the constructional details of this head which are clearly shown in Fig. 5.

A driving mechanism is provided for oscillating the gear segments 43 and 44 to produce an oscillatory movement of each of the lapping wheels 26 and 28 at a comparatively low rate of speed during their combined rapid planetary and slow rotary movements. A speed reduction unit 90 is driven by means of a multi-stepped V-groove pulley 91 (Fig. 1) mounted on the lower end of the shaft of the motor 49. A V-belt 92 drivingly connects the pulley 91 with a multi-stepped V-groove pulley 93 which is mounted on the lower end of the rotatable driving or input shaft 94 of the speed reduction unit 90. A driven or output shaft 95 of the speed reduction unit 90 is provided with a rotatable plate 96 which is in turn provided with a T-slot 97 (Figs. 1 and 4) which serves as an adjustable crank plate. A connecting rod 98 is connected at one end by an adjustably positioned stud 99 which is adjustably supported within the T-slot 97 by means of which the crank motion imparted to the end of the connecting rod 98 may be varied as desired. The forward end of the connecting rod 98 is connected to a stud 100 which is carried by a bracket 101. The bracket 101 is fixedly mounted on the arm 41 adjacent to gear segments 43 and 44. As the rod 98 is moved endwise, due to revolution of the adjustable crankpin 99, an oscillating movement is transmitted through the pin 100, to the bracket 101, to oscillate the arm 41 which in turn oscillates the head 25 and the lapping wheel 28. At the same time, through the intermeshing gear segments 43 and 44, the arm 42 is oscillated which transmits a corresponding oscillatory movement to the lapping head 27 and the lapping wheel 28. By adjusting the crankpin 99 relative to the plate 96, the length of the oscillatory stroke of the heads 25 and 27 together with the lapping wheels 26 and 28, respectively, may be varied as desired. It will thus be seen that the heads 25 and 27 together with their respective lapping wheels 26 and 28 are oscillated simultaneously and in opposite directions during the simultaneous rotary and planetary movement of the lapping wheels 26 and 28.

Any standard speed reduction unit may be employed for reducing the speed of the motor pulley 91 to a suitable speed for oscillating the lapping heads 25 and 27. As illustrated in the drawings, the speed reducing unit 90 which is employed is of the type known as the "Heliocentric" manufactured by the Universal Gear Corporation of Indianapolis, Indiana. The driven or input shaft 94 carries a pair of eccentrics 105 and 106 (Fig. 8). The output or driven shaft 95 is fixedly mounted to a rotatable plunger holder 107 which travels within a stationary internal rack or gear member which is preferably divided into two parts, namely, the internal racks 108 and 109. The plunger holder 107 rotates within the stationary racks 108 and 109 at the rate of one tooth for each rotation of the input shaft 94. The plunger holder 107 is slotted radially and carries a plurality of reciprocable plungers 110 and 111 which are arranged to work into and out of the teeth of the stationary racks 108 and 109.

The racks 108 and 109 are keyed to the casing and have the general appearance of an internal ring gear but with definitely differing tooth shapes, the teeth of the racks 108 and 109 being substantially wedge-shaped. Due to the wedging contact between the arrow-pointed plungers 110 and 111 and the teeth of the racks 108 and 109, respectively, a combination of sliding and rolling wedge action is obtained, forcing rotation with a minimum friction to the plunger holder 107 and the output or driven shaft 95. The input eccentrics 105 and 106 force plungers out under load. A pair of retracting rings 112 and 113 ride in notches formed within the plungers 110 and 111, respectively, to hold them back on the no load part of their cycle of operation.

A single eccentric and set of plungers and stationary racks may be employed but for a maximum smoothness of operation and balance of the working parts, a universal Heliocentric speed reduction unit is employed, having two eccentrics as illustrated, each of which actuates a set of plungers and in operative engagement with a pair of stationary racks. Each set of plungers is timed directly opposite or 180 degrees apart and has a carrying arc of approximately 120 degrees. The total effect is a balanced distribution of driving power over two-thirds of the complete cycle so that a balanced and uniform slow rotation of the output or driven shaft 95 serves to rotate the eccentric or crankpin 99 to oscillate the heads 25 and 27 simultaneously in opposite directions to cooperate with the combined rotary and planetary movements of the lapping wheels 26 and 28 (Fig. 15) to produce the desired break-up movement of the lapping elements, thus producing a highly refined surface on a work piece.

To facilitate removal of finished work pieces and the insertion of work pieces to be lapped into the machine, a power operated lift mechanism is provided whereby the lapping heads 25 and 27 may be simultaneously moved to and from an operative position. In the preferred form, a fluid pressure operated mechanism is employed, comprising a cylinder 115 which is fixedly mounted relative to the base 10 of the machine. A piston 116 is slidably mounted therein and is connected to one end of a piston rod 117. The upper end of the piston rod 117 is connected to an end cap 118 which is fixedly mounted on the upper end of the sleeve 37. When fluid under pressure is admitted to a cylinder chamber 119 below the piston 116, the piston 116 together with the sleeve

37 is moved vertically in an upward direction to raise the head 38 which in turn raises the lapping heads 25 and 27 and also the lapping wheels 26 and 28, respectively, to an inoperative position. Similarly, when fluid under pressure is admitted to a cylinder chamber 120 above the piston 116, a downward movement of the sleeve 37 within the column 36 is obtained, thus moving the lapping heads 25 and 27 to shift the lapping wheels 26 and 28 into operative engagement with the work piece 13.

In order to counterbalance the weight of the head 38 and the parts supported thereon, a counterbalance spring 121 is provided. The spring 121 is a compression spring and surrounds the piston rod 117 and is contained within a central aperture formed in the vertically movable sleeve 37. The spring 121 is interposed between a plate 122 at the base of the column 36 and an adjustable thrust collar or nut 123 which is screw threaded into a threaded aperture at the top of the column 37 (Fig. 1). By adjusting the nut 123 relative to the column 37, the compression of the spring 121 may be adjusted as desired. The compression spring 121 is preferably designed and adjusted so that its compression is sufficient substantially to counterbalance the weight of the head 38 and the mechanisms supported thereby. When the head 38 is moved downwardly under the influence of fluid under pressure, the spring 121 is compressed and serves as a cushion to reduce or cushion the approaching movement of the lapping wheels 26 and 28 as they move into operative contact with the work piece 13.

A fluid pressure system is provided for controlling the admission of fluid under pressure to the cylinder 115. A reservoir 125 is formed as a separate unit at the rear of the base 10 of the machine and is connected to the base by a large tubular member 126 (Fig. 1). Fluid is pumped from the reservoir 125 by a fluid pump 127 which is driven by an electric motor 128. The pump 127 forces fluid under pressure through a pipe 129 to a control valve 130. The control valve 130 is a piston type valve comprising a valve stem 131 having formed integrally therewith valve pistons 132 and 133. In the position of the parts (Fig. 3), fluid under pressure passing through the pipe 129 enters a valve chamber located between the valve pistons 132 and 133 and passes outwardly through a pipe 134 into the cylinder chamber 119 to move the piston 116 upwardly which in turn serves to move the lapping heads 25 and 27 to an upward or inoperative position. During this movement fluid within the cylinder chamber 120 is exhausted through a pipe 135 which passes fluid into an end chamber 136 in the valve 130, from which fluid exhausts through a pipe 137 into the reservoir 125.

When the valve stem 131 is moved toward the left (Fig. 3) into its reverse position, fluid under pressure from the pipe 129 entering the valve chamber between the valve pistons 132 and 133 passes outwardly through the pipe 135 into the cylinder chamber 120 to produce a downward movement of the piston 116 against the compression of the spring 121 to move the bracket 38, lapping heads 25 and 27, and lapping wheels 26 and 28 into operative lapping engagement with the work piece 13. During this movement, fluid within the cylinder chamber 119 is exhausted through the pipe 134, into a chamber 138 at the right-hand end of the valve 130 (Fig. 3), and out through a pipe 139 which exhausts into the reservoir 125. An adjustable relief

valve 140 is provided in the pipe line 129 whereby excess fluid under pressure within the fluid system may be exhausted through a pipe 141 into the reservoir 125.

To facilitate control of the lapping operation, an electrical control apparatus is provided for controlling not only the rotation and gyration of the work piece 13 but also the rotary, planetary and oscillatory movements of the lapping wheel 26. The valve 130 is preferably electrically actuated by means of a solenoid 142 which is operatively connected to the left-hand end of the valve stem 131 and a solenoid 143 which is operatively connected to the right-hand end of the valve stem 131.

Electric power is supplied from a suitable source of power, indicated by the power lines 150 (Fig. 3). An electric starter button 151 is provided to start the lapping cycle and a stop button 152 is provided whereby the cycle may be stopped and the laps returned to an inoperative position at any time during the cycle, if desired. The push buttons 151 and 152 are preferably operated by means of a manually operable lever 153 (Figs. 1, 2 and 10) which projects from the front of the machine base 10. The lever 153 is pivotally mounted on a stud 154 which is fixedly mounted within the base 10 and the push buttons 151 and 152 are located within the base 10 of the machine. When the lever 153 is moved in a counterclockwise direction (Fig. 10), the push button switch 151 is closed which serves to energize the solenoid 142 to shift the control valve 130 toward the left (Fig. 3) to cause a downward movement of the piston 116 and the lapping heads 25 and 27 together with their respective lapping wheels 26 and 28, and at the same time to set an electric time delay relay 155 in motion.

The downward movement of the head 38 shifts an adjustable stop or dog 156 (Fig. 3) into engagement with the actuating roller of the normally open limit switch 157 to close the switch which in turn closes a circuit through a magnetic switch 158 to start the motor 14 and thereby rotate and/or gyrate the work piece 13 and at the same time start the motor 49 so as to rotate, revolve and oscillate the lapping wheels 26 to produce the desired and predetermined lapping operation on the work piece 13. The lapping operation continues for a predetermined time interval according to the setting of the adjustable electric time delay relay 155. After a predetermined time interval has elapsed, the time delay relay 155 serves to energize the solenoid 143 to shift the valve 130 toward the right (Fig. 3) to cause the piston 116 to move upwardly, thus moving the lapping heads 25 and 27 together with their respective lapping wheels 26 and 28 to an upward or inoperative position. During this upward movement of the head 38, the adjustable stop or dog 156 recedes from engagement with the limit switch 157 and the switch 158 opens the circuit to operate the contact 159 which in turn stops the motors 14 and 49 to stop the movement of the work piece 13 and the lapping wheels 26 and 28 so that the finish lapped work piece 13 may be removed from the machine and a new piece of work to be lapped inserted there instead. A push button switch 160a is mounted on the front of the machine base to control the starting and stopping of the motor 128 which drives the fluid pump 127.

For certain types of work, a lapping element having a rectilinear reciprocating stroke is desir-

able. In order to attain one object of this invention, it is desirable to provide a lapping machine in which either a rotary planetarily moved lapping wheel or a reciprocatory lapping stick may be employed, depending upon the nature of the work pieces to be lapped. The lapping wheels 26 and 28 are preferably supported by a tapered shank 160 which mates with or fits a tapered aperture 161 formed within the lower end of the spindles 29 and 35, respectively, so that the rotatable planetarily movable lapping wheels 28 and 26 may be readily removed from the machine when desired.

A reciprocatory lapping stick adapter 162 is provided having a hollow tubular shaped member provided with an aperture 163 which fits an outer peripheral cylindrical surface on the housing 27. The adapter 162 is provided with elongated slots 164 and 165 which are arranged on diametrically opposite sides thereof. A pair of studs 166 and 167 pass through the elongated slots 164 and 165, respectively, and are screw threaded into the housing 27. A thrust collar 168 is provided adjacent to the lower end of the housing 27 and a plurality of studs 169 (Figs. 11 and 13) project downwardly from the thrust collar 168. The studs 169 are surrounded by compression springs 170, the lower ends of which are located within apertures or holes 171 formed in the adapter 162. In the preferred form, a plurality of studs 169 are provided which are symmetrically arranged (Fig. 13) so as to form a yielding device whereby the reciprocable lapping sticks to be hereinafter described may be maintained in operative yielding contact with the surface of the work piece 13 to be lapped.

The adapter 162 is provided with a reciprocable lapping stick holder 173 which serves as a support for a pair of spaced parallel lapping sticks 174 and 175. Each of the lapping sticks is removably supported on the reciprocable holder 173 so that they may be readily removed and replaced when desired. The lapping stick 174 is provided with a holder 176 having a surface 177 (Fig. 12) which mates with a correspondingly shaped surface on the under side of the reciprocable holder 173. The holder 176 is yieldingly held in position on the reciprocable holder 173 by means of a pair of springs 178a and 178, respectively, by means of which the lapping stick holder 176 may be readily detached when it is desired to replace the lapping stick with a new stick or a stick having different abrading characteristics.

Similarly, the lapping stick 175 is mounted in a holder 180 which is similarly yieldably held in position on the reciprocable holder 173 in the same manner that the lapping stick 174 and its supporting holder 176 are mounted. Only one of the mountings has been shown in detail, since they are identical in construction and it is not deemed necessary to duplicate the illustration. The reciprocable holder 173 is arranged to reciprocate longitudinally in a guideway 181 formed in a lower end plate 182 fixed to the lower surface of the adapter 162. A member 183 is fixed to the upper surface of the reciprocable holder 173 and forms a slide member which mates with the slide surface 181 and also slides longitudinally on the plate 182, thus cooperating with the reciprocable holder 173 to form slideways for producing the desired reciprocatory movement of the lapping sticks 174 and 175.

In order to impart a reciprocatory movement to the lapping sticks 174 and 175, a suitable con-

nexion is provided between the spindle 29 and the reciprocable lapping stick holder 173. The member 183 is provided with a transversely extending cut-out portion, forming two thrust surfaces 184 and 185 (Fig. 14) within which a ring 186 is located. The ring 186 serves as a support for an anti-friction bearing 187. A tapered shank 188 mates with the tapered aperture 161 in the lower end of the spindle 29. A crankpin 189 is formed integral with the shank member 188 and fits within the central aperture in the anti-friction bearing 187. It will be readily apparent from the foregoing disclosure that when the spindle 29 is rotated, the crankpin 189 will be revolved to impart a reciprocatory movement to the anti-friction bearing 187 and the ring 186, through the thrust surfaces 184 and 185, to the reciprocatory lapping stick holder 173, so as to impart a reciprocatory movement to the lapping sticks 174 and 175.

Rotary motion of the sleeve 31 (Fig. 11) similarly will be imparted through the crankpin 189 to provide a reciprocatory stroke of the lapping sticks 174 and 175. Due to the fact that the sleeve 31 is rotated at a comparatively rapid rate and the spindle 29 at a comparatively slow rate of speed, a compound reciprocatory movement will be transmitted to the lapping sticks 174 and 175. The rapid rotation of the sleeve 31 will impart a comparatively rapid reciprocation of a relatively long stroke to the lapping sticks 174 and 175 and simultaneous therewith the slow rotation of the spindle 29 will impart a reciprocatory movement to the lapping sticks 174 and 175 which is of a relatively slow speed through a comparatively short stroke. It will be readily apparent from the foregoing disclosure that the reciprocatory lapping sticks 174 and 175 will be provided with a compound reciprocatory stroke which produces a break-up action in abrading or lapping a work piece. In addition to the compound reciprocatory stroke of the lapping sticks 174 and 175, the two heads 25 and 27 are oscillated simultaneously and in the opposite direction, thus imparting a third relative motion of the lapping sticks 174 and 175. At the same time the compound reciprocatory and oscillating movement is imparted to the lapping sticks 174 and 175, the work piece 13 is rotated and gyrated through an irregular path, thus producing a plurality of compound motions which break up the action of the individual abrading particles of the lapping sticks so as to produce a highly refined ultra-finished surface on the work piece 13 being lapped.

It will be readily apparent from the foregoing disclosure that the reciprocable lapping stick adapter 162 may be readily mounted on the heads 25 and 27 by removing the lapping wheels 26 and 28 and sliding the tubular members of the reciprocable lapping stick adapters 162 into supporting engagement with the housings 25 and 27, after which the studs 166 and 167 are inserted in place, thus holding the adapters 162 in position for a lapping operation. When the adapters 162 are removed into an operative position, the tapered shank 188 is moved into operative engagement with the tapered aperture 161 so that the combined rotary motion of the spindle 29 and the planetary motion of the sleeve 31 will be imparted to produce a compound reciprocatory movement of the lapping sticks 174 and 175. Similarly, the adapter 162 may be readily removed from the machine by removing the studs 166 and 167 and withdrawing the

tapered shank 188. It will be readily apparent from the foregoing disclosure that the improved lapping machine may be readily set up for a lapping operation either with rotatable planetarily moved lapping wheels or with a reciprocatory lapping stick adapter, depending upon the nature of the work piece and the surface to be produced thereon.

The operation of this improved lapping machine will be readily apparent from the foregoing disclosure. The machine as set up in Fig. 1 employing rotatable planetarily moved lapping wheels 26 and 28 is set in motion by movement of the control lever 153 which starts the motors 14 and 48, respectively, to set the work piece 13 in motion and at the same time to start a rotary and planetary as well as an oscillatory movement of the lapping wheels 26 and 28, after which the wheels 26 and 28 are moved downwardly into operative engagement with the work piece 13 to be lapped.

If a reciprocatory stick type operation is desired, the lapping wheels 26 and 28 may be readily removed from the spindles 29, after which the lapping adapters 162 (Fig. 11) may be mounted in operative position on the heads 25 and 27, respectively, and the lapping operation may then proceed. The lapping sticks 174 and 175 are provided with a compound reciprocatory motion, that is, a rapid relatively long reciprocatory stroke to which is superimposed a shorter reciprocatory stroke at a slower speed, both of which are combined with an oscillatory movement of the lapping heads 25 and 27, respectively. These combined break-up movements of the lapping sticks together with the combined rotary and planetary movement of the work piece 13 will produce the desired break-up action whereby the lapping sticks will lap the surface of the work piece 13 to a highly refined surface of the required perfection.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

This application covers a modified form of the machine shown in my prior pending application Serial No. 287,985 filed August 2, 1939.

I claim:

1. In a lapping machine having a lapping head, a sleeve rotatably supported in said head, a spindle rotatably and eccentrically supported in said sleeve, means positively to rotate said sleeve, means slowly to rotate said spindle, said spindle being adapted to support a lapping wheel for a rotary and planetary movement, and a reciprocating lapping stick adapter comprising a tubular member adapted slidably to fit a cylindrical surface on said head, a reciprocable lapping stick holder on said adapter, a pair of spaced lapping sticks on said holder and means including a pitman carried by said spindle which is operatively connected with said holder to impart a compound reciprocatory movement to said holder and lapping sticks.

2. In a lapping machine having a lapping head, a rotatable spindle and an eccentric sleeve surrounding said spindle, means positively to rotate said sleeve means slowly to rotate said spindle, and an adapter comprising a tubular member adapted to slidably fit on said head, a reciprocable lapping stick holder on said adapter, an eccentric stud carried by said spindle, operative connections between said stud and said holder whereby rotation of said spindle imparts a slow, relatively short reciprocatory stroke to said holder and lapping sticks and whereby revolution of said sleeve imparts a simultaneously, relatively faster, and longer reciprocatory stroke to said holder and said lapping sticks.

3. In a lapping machine as claimed in claim 5, the combination with the parts and features therein specified, of a head, a tubular member adapted to fit said head, a plurality of elongated slots formed in said tubular member, and studs projecting through said slots and fixedly mounted in said lapping head to facilitate a limited sliding movement of the adapter relative to said lapping head.

4. In a lapping machine as set forth in claim 5, the combination with the parts and features therein specified, of a frame, and adapter including a tubular member adapted to fit on said head, a plurality of elongated slots formed in the sides of said tubular member, studs projecting through said slots and fixedly mounted in said lapping head to facilitate a limited sliding movement of the adapter relative to the head, a reciprocable lapping stick on said tubular member, and yieldable means interposed between the head and adapter yieldably to maintain the lapping sticks in engagement with a work piece.

5. In a lapping machine having a lapping head, a sleeve rotatably supported in said head, a spindle rotatably and eccentrically supported in said sleeve, means positively to rotate said sleeve, means slowly to rotate said spindle, said spindle being adapted to support a lapping wheel for a rotary and planetary movement, and a reciprocating lapping stick adapter comprising a tubular member slidably adapted to fit a cylindrical surface on said head, a reciprocable lapping stick holder on said adapter, an eccentric carried by said spindle, operative connections between said eccentric stud and said holder whereby rotation of said spindle imparts a slow relatively short reciprocatory stroke to said holder and said lapping sticks and revolution of said sleeve imparts a simultaneous, relatively rapid, longer stroke to said holder and said lapping sticks.

6. In a lapping machine having a lapping head, a sleeve rotatably supported in said head, a spindle rotatably and eccentrically supported in said sleeve, means slowly to rotate said spindle, means positively to rotate said sleeve, said spindle being adapted to support a lapping wheel for a rotary and planetary movement, and a reciprocating lapping stick adapter comprising a tubular member adapted slidably to fit a cylindrical surface on said head, a reciprocable lapping stick holder on said tubular member, a pair of spaced lapping sticks fixedly mounted on said holder, and means including a pitman carried by said spindle which is operatively connected with said holder to impart a compound reciprocatory movement to said holder and lapping sticks.

HERBERT S. INDGE.

CERTIFICATE OF CORRECTION.

Patent No. 2,284,056.

May 26, 1942.

HERBERT S. INDGE.

It is hereby certified that error appears in the above numbered patent requiring correction as follows: In the drawings, insert the figure shown below as a part of Sheet 2 -

Fig.15

same Sheet 2, Figure 2, for the reference numeral "160" read --160a--; Sheet 5 of the drawings, Figure 12, for the numeral "177" designating a spring read --178a--; and that the said Letters Patent should be read with this correction therein that the same may conform to the record of the case in the Patent Office.

Signed and sealed this 11th day of August, A. D. 1942.

(Seal)

Henry Van Arsdale,
Acting Commissioner of Patents.
